PNEUMATIC THREAD REMOVER FOR WEFT
REPLENISHING LOOMSRichard G. Turner, Worcester, Mass., assignor to
Crompton & Knowles Loom Works, Worcester,
Mass., a corporation of Massachusetts

Application May 28, 1949, Serial No. 96,083

7 Claims. (Cl. 139—256)

1

This invention relates to improvements in pneumatic thread removers for weft replenishing looms and it is the general object of the invention to provide simple means by which the remover can be held in either its idle non-operating or operating thread pick-up position.

A form of pneumatic thread remover already proposed by me employs a tube having a depending lip to engage the thread of the outgoing bobbin and position it for pneumatic attraction as the lay moves rearwardly. The thread extends along the race plate of the loom between the cloth and the shuttle box and is ordinarily supported on a mass of deformable material, such as plush, and the lip when in thread pick-up position extends downwardly into the plush to a position below the level of the thread. The remover tube is lowered by a force derived from the transerrer arm, but experience shows that because of vibration of the loom or rebound of the remover the pick-up lip does not always remain in a low enough position to catch the thread and the latter can under these conditions move rearwardly with the lay without being directed to the intake mouth of the thread remover.

It is an important object of the present invention to provide simple means by which the thread remover will be held in its low position with the lip so located as to engage and direct the thread to the intake mouth of the remover. This result as set forth hereinafter is accomplished by the use of permanent magnet means held in fixed position and so located as to hold the remover tube in proper position to pick up the thread.

It is also desirable to be able to hold the thread remover in its normal or inactive raised position, and it is a further object of the invention to provide other magnetic means to hold the remover in its normal position. The thread remover is acted upon positively by two parts of the loom one of which is the transerrer arm which lowers the remover to its thread pick-up position and the other of which is a regularly acting resetter which returns the thread remover to its normal position as the lay approaches its back center position next following a bobbin transferring operation. It is a further object of the invention to have the aforesaid magnetic means so located that a single magnetizable armature rigid with the carrier for the remover tube can co-operate with one or the other of the magnetic means to hold the remover either in normal raised or operating lowered position.

It is essential that the remover when being moved to thread pick-up position shall be prevented from striking a rigid part of the lay and with this end in view it is a further object of the invention to have the magnetic means corresponding to the thread pick-up position of the

2

remover act also as a stop. For this purpose the magnetic means is preferably secured to a mounting adjustable concentrically around the stud on which the transerrer arm is mounted.

With these and other objects in view which will appear as the description proceeds, the invention resides in the combination and arrangement of parts hereinafter described and set forth.

In the accompanying drawings, wherein a convenient embodiment of the invention is set forth:

Fig. 1 is a side elevation of part of a weft replenishing loom having the invention applied thereto, the lay and part of the loom frame being shown in cross section, and the thread remover being indicated in its normal raised or idle position.

Fig. 2 is a view similar to part of Fig. 1 but showing the thread remover in its lowered operating thread pick-up position.

Fig. 3 is an enlarged front elevation looking in the direction of arrow 3, Fig. 1, illustrating the manner of holding the mounting for the magnetic means in fixed position.

Fig. 4 is a side elevation looking in the direction of arrow 4, Fig. 3.

Fig. 5 is an enlarged detailed section on line 5—5, Fig. 3, and

Fig. 6 is a horizontal section on line 6—6, Fig. 4. Referring particularly to Fig. 1, the loom frame

10 has mounted thereon a support 11 provided with a pivot 12 for a magazine M which in the present instance is of the rocking type and provided with two stacks of reserve bobbins (not shown). The support 11 has mounted thereon a

transerrer stud 15 held in fixed position and providing a pivotal support for the bobbin transerrer arm 16 which is normally in raised position. Extending laterally from the transerrer arm is a depressing member 17 which may take

the form of a stud or pin secured to the transerrer arm and having mounted thereon an eccentric 18 held in fixed position with respect to the stud by a clamping nut 19. The eccentric is capable of adjustment around the stud 17 for co-operation with a rearwardly extending arm 20

45 of an angularly movable carrier designated generally at 21 pivoted on stud 15 for movement therearound.

The carrier has front and back vertical arms

50 25 and 26, respectively, in which is slidably mounted a rod 27 having secured thereto a collar 28 located between the arms 25 and 26. A compression spring 29 between the front arm 25 and the collar 28 normally urges the rod rearwardly to the position shown in Fig. 1.

The rear part of rod 27 supports a pneumatic thread remover R comprising a hollow tube the lower end of which is provided with an intake mouth 30. A thread pick-up lip 31 extends down-

wardly from the tube behind the intake mouth and is directed forwardly. A plate 32 secured to the remover R is fastened to the rear end of rod 27. The remover R extends into a hose or flexible tube 35 which connects with some form of pneumatic mechanism which will create sub-atmospheric pressures within the tube, the remover, and at the thread intake mouth 30.

The lay L of the loom is provided with a shuttle box 36 which receives the shuttle S, and the race plate 37 has extending thereacross a body 38 of deformable material, such as a pile fabric. The thread of a depleted shuttle bobbin in shuttle S extends from the selvage along the race plate 37 and over the deformable material 38 into the shuttle box. When a weft replenishing operation occurs the transfer arm 16 is depressed and eccentric 18 engages arm 20 to rock the carrier 21 in a counter-clockwise direction as viewed in Fig. 1 to move the carrier and remover R to their operating thread pick-up position with the lip 31 located below the top of the mass 38 of deformable material and behind the thread of the depleted bobbin. This ordinarily occurs as the lay approaches its front center position, and as the lay recedes the thread, being frictionally held by the pile fabric 38, is moved rearwardly toward the lip 31 and the latter directs the thread toward the intake mouth 30 to subject the thread to pneumatic attraction. As the shuttle is picked out of the box that part of the thread extending into the shuttle box is released and drawn upwardly into the remover tube. On a subsequent pick of the loom the thread will be cut at the selvage and will be drawn into the remover.

During the backward motion of the lay immediately following bobbin transfer a resetter rod 39 rises to engage a lifting shelf 40 on the carrier 21 to rock the latter in a clockwise direction as viewed in Fig. 2 and returning the remover R to its normally raised idle position.

The matter thus far described may be similar to mechanism heretofore proposed by me and operates in the usual manner.

In carrying the present invention into effect simple means is provided for holding the remover R in its down or thread pick-up position so that the lip 30 will be embedded deeply enough in the pile fabric 38 to be under the thread of the outgoing bobbin as the lay moves backwardly subsequently to a bobbin changing operation. It is also necessary to be able to provide means for holding the remover R in its normal idle raised position. In order to maintain the remover in the two positions which it may occupy I provide a mounting 45 which may be made of sheet metal preferably though not necessarily non-magnetic. The lower end of the mounting has a hole 45 therein which fits stud 15, and has a slot 47 therein preferably concentric with the stud 15 through which extends a screw 48 tapped into the support 11. The screw can be tightened to hold the mounting in adjusted angular position around the stud 15.

The upper end of the mounting is provided with a pair of spaced stationary permanent magnets 55 and 56. These magnets are similar and each comprises a body 57 permanently magnetized and mounted on a stud 58 having a head 59 engaging the left end of the magnet, see Fig. 3, and extending through the upper part of the mounting 45 and held in position thereon by a lock nut 60. The ends of the magnet are of opposite polarity and each magnet is adjustable around the stud 15 by having its supporting stud 58 ex-

tended through a slot 61 in the mounting 45. Thus, the front magnet 55 can be moved backwardly or forwardly on the mounting 45 by loosening its lock nut 60 and adjusting it along the slot 61 until the magnet is in the desired position, after which the lock nut 60 can be tightened. A similar adjustment can be made for the rear permanent magnet 56, each magnet being adjustable toward and from the other and relatively to the mounting 45 and in a direction around the stud 15 which provides a common axis for the transfer arm, the carrier 21, and mounting 45.

In order that the magnets may control the position of the carrier 21 the latter is provided with an upwardly extending part or arm 65 which may be given a 90° twist to provide an armature 66 between the magnets 55 and 56 which is broad enough to extend across each of them. This armature is preferably integral with the carrier 21 which is made of magnetic material, such as sheet steel. The carrier is held in position on the stud 15 between a collar 67 and a washer 68 which is held against a shoulder 69 of the stud 15 by a nut 70 threaded on the reduced end 71 of stud 15. The parts are so related that the carrier 21 is free to rotate on the stud 15.

In operation, the thread remover R and parts associated therewith will normally be in the position shown in Fig. 1 with the armature 66 held by the permanent magnet 55. When the weft replenishing mechanism operates descent of the transfer arm 16 will cause the eccentric 18 to engage arm 20 and rock the carrier 21 to the thread pick-up position shown in Fig. 2, thus causing the armature 66 to move rearwardly away from magnet 55 and move within the range of attraction of the rear magnet 56. Because of the fact that the latter magnet serves as a stop and can be adjusted around stud 15 the lowest position which the lip 31 can reach can be adjusted to prevent the lip from striking a solid part of the lay. The magnet 56 will hold the remover R in its correct down position with the lip low enough to pass under the outgoing thread and direct it to the intake mouth.

As the lay approaches its back center position resetter rod 39 will rise and engage lifting shelf 40 and return the carrier to its normal raised position, whereupon the armature 66 will be established in holding relation with respect to the front magnet 55 and the remover R will be held in its normal idle position until the next replenishing operation of the loom. It is obvious that angular adjustment of the mounting made possible by the screw 48 permits adjustment of the magnets around the axis of stud 15 independently of the adjustments which each magnet has because of its supporting stud 58. It will also be seen that for all adjustments of the magnets their retaining force will be essentially the same since they will be at the same distance from the axis of stud 15 in any of their adjusted positions.

Having thus described the invention it will be seen that changes and modifications of the foregoing specific disclosure may be made without departing from the spirit and scope of the invention.

What is claimed as new is:

1. In control means for the pneumatic thread remover of a loom having a weft replenishing mechanism including a bobbin transfer arm, a carrier for the remover capable of being either in normal idle position or in operating thread pick-up position, a pivot stud for the trans-

ferrer arm around which a carrier moves, a mounting on the stud, means holding the mounting in adjusted angular position around the stud, magnetic means on the mounting normally effective to maintain the carrier in normal position, the transerrer arm incident to a weft replenishing operation of the loom moving the carrier from the normal position thereof to said pick-up position thereof, and other magnetic means on said mounting holding the carrier in said pick-up position.

2. In control means for the pneumatic thread remover of a loom having a weft replenishing mechanism including a bobbin transerrer arm, an angularly movable carrier for the thread remover capable of being either in normal idle position or in thread pick-up position, a mounting, means holding the mounting in adjusted angular position, a common pivotal support for the transerrer arm, carrier, and mounting, the transerrer arm incident to a replenishing operation of the loom moving the carrier from the normal position thereof to the pick-up position thereof, magnetic means on the mounting cooperating with the carrier holding the latter in said pick-up position, and a resetter acting on the carrier subsequent to said weft replenishing operation moving the carrier away from said magnetic means and returning said carrier to said normal position thereof.

3. In control means for the pneumatic thread remover of a loom having a weft replenishing mechanism including a bobbin transerrer arm, a carrier for the thread remover capable of being either in normal idle position or in thread pick-up position, a stud forming a common pivotal support for the transerrer arm and the carrier, a mounting angularly adjustable around said stud, means holding said mounting in angularly adjusted position, a pair of magnetic means on the mounting for cooperation with said carrier, one of said magnetic means normally holding the carrier in the normal position thereof and the other magnetic means capable of holding the carrier in said thread pick-up position thereof, the transerrer arm incident to a weft replenishing operation of the loom moving the carrier away from said one magnetic means into holding relation with respect to the other magnetic means, and a resetter for the carrier operative subsequent to said weft replenishing operation moving said carrier away from said other magnetic means into holding relation with respect to said one magnetic means.

4. In control means for the pneumatic thread remover of a loom having a weft replenishing mechanism including a bobbin transerrer arm, an angularly movable carrier for the thread remover capable of being either in normal idle position or in thread pick-up position, a stud forming a common pivotal support for the transerrer arm and the carrier, a mounting movable angularly around and supported on said stud, means holding the mounting in angularly adjusted position, a pair of spaced magnetic means on the mounting, a part on the carrier made of magnetizable material located between said magnetic means, and a resetter for the carrier, the transerrer arm incident to a weft replenishing operation of the loom moving said carrier to the thread pick-up position thereof and moving said magnetizable part of the carrier away from one of said magnetic means into holding relation with respect to the other magnetic means, and said resetter subsequently returning said carrier to

the normal position thereof and moving said magnetizable part into holding relation with respect to said one magnetic means.

5. In control means for the pneumatic thread remover of a loom having a weft replenishing mechanism including a bobbin transerrer arm, a stud on which the transerrer arm is angularly movable, a carrier for the thread remover angularly movable on said stud capable of being either in normal idle position or in thread pick-up position, a mounting capable of angular adjustment around said stud, means holding the mounting in angularly adjusted position, said carrier having a part thereof made of magnetizable material, and a pair of magnetized stop and holding means on said mounting disposed on opposite sides of said part of the carrier, the latter being held in the normal position thereof by one of said magnetic means, said carrier being moved to the pick-up position thereof by the transerrer arm incident to a weft replenishing operation of the loom, and the other magnetic means serving as a stop to limit movement of the carrier toward said pick-up position and also cooperating with said part of the carrier to hold the latter and the remover in said thread pick-up position.

6. In control means for the pneumatic thread remover of a loom having a weft replenishing mechanism including a bobbin transerrer arm, an angularly movable carrier for the thread remover, a common pivotal support for the carrier and transerrer arm, part of the carrier being made of magnetizable material, a pair of stationary spaced magnetic means cooperating one at a time with said part of the carrier, each magnetic means serving as a stop and also as a holding means for said part of the carrier, one of said magnetic means normally attracting said part of the carrier to hold the latter and thread holder in normal idle position, the transerrer arm incident to a weft replenishing operation moving the carrier and thread remover to thread pick-up position, and the other magnetic means serving as a stop for said part of the carrier limiting motion of the latter and also effective to hold said part of the carrier to maintain the latter and thread remover in thread pick-up position.

7. In control means for the pneumatic thread remover of a loom having a weft replenishing mechanism including a bobbin transerrer arm, a carrier for the thread remover, a common pivotal support for the transerrer arm and the carrier, a pair of spaced permanent magnets held in fixed position with respect to the weft replenishing mechanism, a magnetizable armature on the carrier moving with the latter and located between said permanent magnets, one of said permanent magnets cooperating with the armature to maintain the carrier and the remover in normal idle position, the transerrer arm incident to a weft replenishing operation of the loom moving the carrier and thread remover to thread pick-up position in which the other permanent magnet cooperates with said armature to hold the carrier and remover in pick-up position, and a resetter operating subsequent to said weft replenishing operation moving the armature away from said other permanent magnet into holding relation with said one permanent magnet.
